UNITED STATES PATENT OFFICE.

AUGUST THOMSEN, OF GLENDALE, NEW YORK.

CALIPERS.

No. 868,896.

Specification of Letters Patent.

Patented Oct. 22, 1907.

Application filed May 22, 1906. Serial No. 318,121.

To all whom it may concern:

Be it known that I, AUGUST THOMSEN, a citizen of the United States, residing at Glendale, county of Queens, and State of New York, have invented certain 5 new and useful Improvements in Calipers, of which the following is a specification.

My invention relates to calipers or what may otherwise properly be termed gage micrometers designed for the use of machinists and other artisans in taking accurate and fine measurements, and has for an object the 10 production of an instrument of this character, which shall be simple and quick-acting in its adjustment to inches or objects of widely varying sizes, and which shall also be capable of thereafter being moved to the 15 smallest fractions thereof.

I will describe a caliper embodying my invention and then point out the novel features thereof in claims.

In the accompanying drawing Figure 1 represents a side elevation of a caliper embodying my invention, 20 the jaws being moved away from each other to give a distance of 2 inches. Fig. 2 is a longitudinal section thereof. Fig. 3 is an end view of Fig. 1 on a larger scale. Figs. 4 and 5 are sectional elevations taken on the line 4, 5, of Fig. 2, the former view showing the 25 parts when in position for use in taking fine and accurate measurements, and the latter view illustrating the parts in their position for use in taking measurements by inches.

Similar reference characters designate corresponding 30 parts in all the figures of the drawing.

Referring to said drawing, A designates my improved caliper, which is here shown as comprising a bar a, which may be graduated on one or both sides into 35 inches and fractions of inches of varying decimals, and a movable jaw b, movable on said bar a and preferably provided with a graduation b¹. The bar a is provided at one end with extensions or fingers a², which may correspond with similar extensions or fingers b², on the end of the bar a, so that they will register when the movable 40 jaw is moved to its extreme position toward that end of the bar a.

The bar a is provided on its lower edge, preferably with a longitudinal groove a¹, in which a feather or spline b³, on the movable jaw moves, which acts to assist in maintaining the latter in its proper relation with the bar a and the lower edges of the walls of the groove a¹, are provided with threads adapted to be engaged by a worm wheel c, carried on one end of a shaft d which rests within an opening c¹ in the movable jaw. The 45 shaft d passes through an eccentrically arranged opening in a sleeve f, and has on its opposite end, a nut g, having a hub g¹ which is graduated, as shown, so that when the worm wheel is in engagement with the threads on the bar a and rotation given to the nut g, each graduation on the hub will move the movable jaw 50 a very slight distance, according to the pitch of the

worm, thereby permitting of most minute adjustment of the caliper.

The sleeve f is supported in an opening h in the movable jaw b, and has at its end a nut f¹ so that by giving 60 rotation thereto in one direction or the other, the sleeve will be moved to bring the worm wheel into or out of engagement with the threads on the bar a, which, in the first instance permits of gradual and accurate adjustment of the movable jaw b, and in the other instance 65 permits it to be quickly moved along the bar a, to permit of rapid and widely varying measurements being made.

In order to give the worm wheel a tendency to incline to move toward and the more firmly engage the threads 70 on the bar a, I prefer to provide a spiral spring s for the sleeve f, which is reduced to receive said spring. One end of this spring is secured to the nut g and the other end is bent, as shown, to enter a groove s¹ in the movable jaw b, or in any other appropriate or convenient 75 manner. Of course, I may dispense with this spring without impairing the caliper or in any way affecting its general efficiency, as will be readily obvious to those skilled in the art to which my invention appertains.

To prevent any possible chance of longitudinal 80 movement of the shaft and otherwise insure accurate engagement of the worm gear with the threads on the bar a, I may provide a tension spring t which is placed in a recess in the movable jaw b adjacent the worm gear c and against which one end of the spring will press. 85 This arrangement serves to maintain the worm gear in the same longitudinal relation with the movable jaw at all times, and renders its adjustment more accurate, although, of course, the worm gear may be so accurately fitted between the walls of the opening c¹ as to 90 make the use of the spring t unnecessary, in which event, I may dispense with it.

The operation of my invention may be understood from the foregoing, but the following brief description thereof may be deemed necessary. When it is desired 95 to adjust the movable jaw by inches, to use it upon objects of widely varying sizes, the nut f will be turned to the left, which has the effect of turning the sleeve f about one half rotation, and, owing to the eccentric relation of the shaft d therewith, the latter will be moved 100 so as to bring its attached worm wheel out of engagement with the threads on the bar a, permitting the movable jaw to be rapidly moved along the bar b to the exact, or approximately the exact distance required. Should it, however, be required to secure a finer and 105 more accurate adjustment of the movable jaw b, then the nut f¹ will be turned to the right, moving the sleeve f into such position as to bring the worm wheel into engagement with the threads on the bar a, when, by rotation of the nut g in either direction, the movable 110 jaw will be caused to move along the bar a in a manner similar to such instruments now in use, the graduation

thereon registering with the graduations in the bar *a* and giving the proper measurements. Of course, the 0 or zero mark on the hub *g*¹ of the nut *g* will first be brought to register with the graduation mark on the 5 movable jaw *b* and each graduation on the hub *g*¹ will thereafter determine the movement of the movable jaw *b* without paying any attention whatever to the vernier.

What I claim as my invention is:

- 10 1. A calliper or gage micrometer comprising a flat bar having graduations on one or both of its sides and threads along one edge thereof and having also a longitudinal groove, a movable jaw having a projection adapted to slide in said groove in the bar and a graduation thereon to 15 register with the graduations on the bar, a worm gear carried by said movable jaw, and an eccentric for throwing said worm into and out of engagement with the threads on

the bar—to permit of gradual or rapid adjustment of the movable jaw.

2. A calliper or gage micrometer comprising a bar having 20 graduations on one or both of its sides and threads along one edge thereof and having also a longitudinal groove, a movable jaw having a spline adapted to slide in said groove in the bar and a graduation thereon to register with the graduations on the bar, a worm gear carried by 25 said movable jaw, an eccentric for throwing said worm into and out of engagement with the threads on the bar, and a spring for keeping the eccentric in position, whereby the worm is normally held out of engagement with the teeth on the bar.

In testimony whereof I have signed my name to this specification in the presence of two subscribed witnesses.

AUGUST THOMSEN.
